(57) **CLAIM**

The ornamental design for a bicycle helmet, as shown and described.

DESCRIPTION

FIG. 1 is a top left side perspective view of a bicycle helmet showing my new design, which is a mirror image of a top right side perspective view;

FIG. 2 is a front view thereof;

FIG. 3 is a top view thereof;

FIG. 4 is a top right side perspective view thereof, which is a mirror image of a top left side perspective view thereof; and,

FIG. 5 is a back right side perspective view thereof, which is a mirror image of a back left side perspective view thereof. The broken lines illustrate portions of the bicycle helmet that form no part of the claimed design.

1 Claim, 5 Drawing Sheets
